UNITED STATES PATENT OFFICE.

HUGH C. BOYER, OF PORTLAND, OREGON.

CLOTHES-DRIER.

1,054,271.

Specification of Letters Patent. Patented Feb. 25, 1913.

Application filed May 28, 1912. Serial No. 700,204.

To all whom it may concern:

Be it known that I, HUGH C. BOYER, a citizen of the United States, residing at Portland, in the county of Multnomah and 5 State of Oregon, have invented certain new and useful Improvements in Clothes-Driers, of which the following is a specification.

This invention pertains to an improvement in clothes driers, and has for its object to 10 provide a rack which is adapted to be set up on the floor about a hot air register, in such manner that articles may be suspended within it to receive the current of air coming from the register.

15 A further object is to provide such a device in which articles may be arranged in small area and quickly dried, which device is capable of being folded into small space for storage.

20 I accomplish these and other objects by the mechanism illustrated in the accompanying drawing, in which—

Figure 1 is a perspective elevation of the device, as in use. Fig. 2 is a top view in 25 collapsed position. Fig. 3 is a slight modification showing a means of attaching the supporting rods to the frame.

Referring to the drawing in detail, 1 designates the upper bars of a frame made substantially in the form of a cube. Each of the lateral faces *a*, *b*, *c* and *d* of the frame 30 consists of a rectangular frame which is hinged to its contiguous member, consecutively from *a* to *d* upon hinges 3, the members *a* and *d* being hinged upon their inner faces while *b* and *c* are hinged upon their outer faces, so that the four sides may be erected upon the floor about the register 14, the members uniting each with the other in 40 a neat union, and the free edges of members *a* and *d* may be secured together, if desired, by any convenient means. Upon the inner faces of the vertical frames is secured a covering of canvas 7, though oil-cloth or 45 other suitable fabric may be employed. When the side frames thus covered are in working position, as seen in Fig. 1, the air from the register is directed upwardly, to

pass through the articles and out at the open upper end.

50 In opposing bars at the upper side of the frame are formed a plurality of oppositely disposed notches 2 arranged in spaced relation along the upper faces thereof. In each opposing pair of these notches is placed a 55 rod 5, over which may be suspended any article 9, above the register in the floor. The rods may be disposed very close together or at any convenient distance apart, and in this manner a great many articles may be supported in an exceedingly small space, and at the same time, be in a measure concealed 60 from view. The rods, when not in use are supported in pocket 8 and keeper 4, upon one of the vertical frames. In Fig. 3 the rod 10 65 is shown mounted in one of the upper frame bars, in an eye 13, and engaged by means of a hook 12 upon a pin 11, in the opposite bar. By this means they are always attached to the frame where they are to be used, and 70 can not become lost.

Having described my invention, what I claim as new and desire to secure by Letters Patent, is—

1. A drying rack comprising a quadrilateral frame, having closed sides, with open upper and lower ends, and parallel supporting rods anchored in spaced relation across the top of the frame.

75 2. A drying rack comprising a quadrilateral frame having vertical side members hinged together at their adjacent edges, each side member being covered with fabric, and a plurality of parallel rods supported in spaced relation across the open upper end of 80 the frame.

3. A drying rack comprising a frame work consisting of a plurality of vertical side members hinged together at their adjacent edges, so that said members may be collapsed to lie one upon another, each side member being covered with fabric and disposable in continuous series to form a vertical conduit, and a plurality of supporting rods pivotally secured along the upper face 85 of one side member and adapted to be en-

gaged upon the upper face of the opposite side member.

4. A drying rack comprising a vertical frame having a continuous lateral member with open upper and lower ends, and supporting rods anchored across the top of the frame.

In testimony whereof I affix my signature in presence of two witnesses.

HUGH C. BOYER.
